CONTACT PRINTING APPARATUS

Albert Baril, Jr., and Irvin H. De Barbieris, New Orleans, La., assignors, by mesne assignments, to Kalvar Corporation, New Orleans, La., a corporation of Louisiana

Filed Apr. 12, 1954, Ser. No. 422,372

3 Claims. (Cl. 95—77.5)

This invention relates to a contact printing apparatus of the type capable of reproducing from a negative or master copy a positive print or other reproduction and its principal object is to provide a simple, efficient and reliable apparatus for automatically exposing for the required time super-imposed positive and negative elements and sequentially separating and ejecting the negative and developing the positive and finally ejecting it, all in a matter of a few seconds.

Further objects relate to various features of construction and will be apparent from a consideration of the following description and the accompanying drawings, wherein:

Fig. 1 is a side elevation, with parts in section, showing the essential separating mechanism of a contact printing apparatus constructed in accordance with the present invention;

Fig. 2 is a section on the line 2—2 of Fig. 1;

Fig. 3 is a plan view of an index card or holder carrying the negative or master copy;

Fig. 4 is a plan view of an index card or holder carrying the positive element or print; and

Fig. 5 is an enlarged perspective of the separator or deflector member, showing the manner in which the cards are separated after exposure.

The particular embodiment herein shown for the purpose of illustration is designed to reproduce from a negative or master copy, such as a microfilm negative carried by an index card, a positive print which is carried by a card having an offset peripheral portion, the process employed being the so-called diazo type or the like which requires an exposure of the superimposed negative and positive elements, followed by an exposure of the positive to a predetermined degree of heat so as to develop the image. Such a process is described in Baril et al. Patent 2,911,299, issued November 3, 1959, to which reference may be had for a more complete disclosure.

Referring to Figs. 1 and 2, the apparatus comprises a box-like structure 1 having front, side and rear walls 2, 3, 4, 5 and an interior partition 6 extending vertically from the top to the bottom wall so as to divide the interior into two compartments 8 and 10. The front wall 2 is formed with vertically aligned openings or windows 11 and 12 the utility of which is hereinafter pointed out.

Mounted within the lower part of compartment 8 is an exposure drum 14 comprising a transparent or light permeable cylindrical shell 15 carried by spaced annular members 16 of generally Z-shaped cross-section. A plurality of smaller rollers 18, mounted on studs 20 carried by the wall 3 and partition 6, engage the inner peripheries of the annular members 16 so as to support the drum for rotation about a horizontal axis.

Mounted in the upper part of the compartment 8 is a developer drum 22 comprising a cylindrical shell 24 of metal or other suitable heat-conducting material, the inner ends of which are recessed to receive supporting rolls 25 mounted on studs 26 carried by the wall 3 and partition 6, the rolls 25 being arranged to support drum 22 for rotation about an axis parallel to that of drum 14.

Disposed about the drum 14 are four belt-guiding rollers 30, 31, 32 and 33, each having shafts rotatably

mounted in bushings carried by the wall 3 and partition 6; and in like manner four belt-guiding rollers 35, 36, 37 and 38 are disposed about the drum 22. The inner ends of the shafts of rollers 33 and 35 extend through the partition 6 into compartment 10 and carry gears 40 and 41 which are interconnected by an idler gear 42 so as to rotate in the same direction. The bushings supporting the rollers 31 and 37 are mounted in transverse slots 45 and 46, and are connected with adjusting screws 47 and 48 which provide take-ups for the conveyor belts.

Although but a single conveyor belt may be used it is found preferable to employ a conveyor belt for each drum and to this end a belt 50 extends about rollers 30-33 and the inner half of the drum 14; and likewise a second conveyor belt 52 extends about rollers 35-38 and the inner half of drum 22.

Between the drums 14 and 22 is a transfer conveyor which comprises a pair of vertically spaced rollers 54 and 55, each mounted on shafts rotatable in bushings carried by wall 3 and partition 6. The inner end of the shaft of roller 54 extends through the partition 6 into compartment 10 and carries a gear 56 (Fig. 1). A conveyor belt 58 extends about the rollers 54 and 55, and the construction and arrangement of parts are such that the belt 58 contacts the belts 50 and 52 as they travel about rollers 33 and 35, respectively, thus cooperating with these belts in transferring a card carrying an exposed print from the drum 14 to the drum 22, as hereinafter more fully explained. In order to insure proper tensioning of the belt 58 a take-up roll 60 is mounted in adjustable bearings 62 so as to engage the outer run of the belt, as shown in Fig. 1.

Mounted in the space between the peripheries of drum 14 and rollers 33 and 35 is a separator member 64 (Figs. 1 and 5) consisting of an elongate piece of sheet metal, one edge portion of which is bent upwardly to form a projecting part or lug 65 which intercepts the negative print while permitting the duplicate to pass over the guiding edge 66. The intercepted negative is guided downward by the lug 65 and passes along the underside of this edge. The opposite longitudinal edge 68 is bent downwardly so as to deflect this card toward the surface of drum 14. The inner end of the separator is bent upwardly to provide a bracket 70 by means of which the separator may be rigidly secured to the partition 6.

A horizontally disposed card-receiving shelf 72 (Fig. 1) is supported by partition 6 so that its outer end overhangs the lower edge of window 11 and its downwardly curved inner end terminates above the roller 30; and likewise a similar shelf 74 is associated with the drum 22 and window 12 so that the card carrying the positive print drops downwardly thereon where it may be readily removed.

Mounted within the lower part of compartment 10 is a socket 76 (Fig. 2) which holds an ultra-violet light lamp 78 projecting through a shielded opening in partition 6 into the interior of the drum 14, it being understood that the socket is electrically connected to a voltage supply and a starter, in the conventional manner. A blower 77 (Fig. 2), controlled by a separate switch, supplies cooling air through an opening in the lamp housing, exhaust being through the opposite open end of the drum. Between the ultra-violet lamp 78 and that section of the inner periphery of the shell 15 facing the window 11 is a shield 80 fastened to the partition 6 which prevents radiations from passing outwardly, thus obviating the possibility of subjecting a positive to premature exposure, while simultaneously acting as a reflector increasing the radiation intensity on the surface where exposure takes place.

Mounted at the upper part of the partition 6 is a heating coil 81 (Fig. 1) which extends into the interior of

the drum 22 so as to heat the shell 24 by radiation, it being understood that the coil 81 is electrically connected in a circuit having conventional controls including the thermostat 82 extending the length of the drum by means of which the temperature of the drum may be adjusted to attain the desired developing temperature.

Adjustably mounted on a bracket 84 within compartment 10 is a motor 86 having reducing gears with the drive shaft connected to a flexible coupling 88 which in turn is connected to the shaft of roller 33. Between the gear 40 and coupling 88 is a gear 90 (Fig. 2) meshing with gear 56 carried by the shaft of roller 54, the design of gears 40-42 and 90 being such that all ten rollers are driven at the same peripheral speed. The motor 86 is connected in an electric circuit having conventional controls by which the speed of the rollers may be varied to attain desired periods of exposure.

With the construction and arrangement thus described the rollers 33, 35 and 54 are positively driven by motor 86 and these rollers drive conveyor belts 50, 52 and 58 which in turn drive the other rollers as well as the drums 14 and 22. Since the peripheral speed of all rollers and both drums are the same, the travel of the print-carrying cards is uniform from the entrance to the exit, and by varying the speed of motor 86 the rate of travel and hence the period of exposure may be varied.

As above noted, the particular apparatus herein shown is designed to reproduce positive prints from a microfilm negative and, as shown in Figs. 3 and 4, the negative microfilm print N is conveniently mounted on the marginal portions of a window or opening formed in a conventional index card C which may carry identifying indicia and other data; and likewise the positive print P is similarly mounted on an index card C'. In order to insure separation of the cards after exposure, one of them is formed with a peripheral portion offset with respect to the other thereby to provide a salient portion or projection engageable by the lug 65, as hereinafter more fully explained and completely described and claimed per se in our Patent 2,731,263. To this end the corner of card C' may be cut off, as indicated at 95 (Fig. 5), so that the corresponding corner of card C provides, in effect, the offset or peripheral projection engageable with the lug 65.

A summary of the operation of the apparatus is as follows:

Assuming that the motor 86, blower 77, lamp 78, and heating element 81 have been turned on, that the motor speed is properly adjusted, and that the drum 22 is at the desired temperature, the card C carrying a negative N is first superimposed on the card C' so that the unexposed print P registers with the negative N, and while thus held the cards are inserted through window 11 so that their leading edges enter the bite of the drum 14 and belt 50. The drum and belt carry the cards in a clockwise direction, as indicated by the arrow, thus exposing the positive print P to the ultra-violet light passing through the shell 15 and the negative. As the leading edge of the cards emerge from the nip of the drum and belt, the lug 65 engages the uncut corner of the card C deflecting it downwardly while the cut-off corner of card C' clears the lug 65 and advances into the bite of belts 50 and 58 as illustrated in Fig. 5.

The card C is deflected downwardly along the outer face of drum 14 and when its trailing end is free from the belt 50, it drops into shelf 72 from which it is removed. Meanwhile the card C' is carried upwardly by the upper run of belt 50 and inner run of belt 58, and its leading edge enters the bite of belts 52 and 58 which carry the card into the bite of belt 52 and drum 22. The card C' then travels about the drum 22 which heats the exposed print P to a temperature sufficient to develop the latent image and as the card emerges from the nip of the belt 52 and drum 22 it drops down onto shelf 74 from which it is removed.

In this manner the print P is exposed, separated from

the negative N, developed and discharged in a matter of a few seconds, usually of the order of one half minute or less. By repeating the process as many positive prints or reproductions may be secured as is desired.

5 While we have shown and described one desirable embodiment of the invention, it is to be understood that this disclosure is for the purpose of illustration and that various changes and modifications may be made without departing from the spirit and scope of the invention as set 10 forth in the appended claims.

We claim:

1. Apparatus for copying comprising a source of radiations of a type to which copying material is sensitive for exposure to said copying material and an original to be copied as a plied combination to thereby record a latent image upon the copying material in accordance with the original to be copied, developing means for said exposed copying material mounted in vertically spaced relation to said source of radiations, first engaging means transparent 15 to said radiations for spacing the plied combination a predetermined distance from said radiations source for exposure thereby, first belt means for receiving the plied combination and passing the same into engagement with said first engaging means, means mounting said first belt 20 means for movement in an endless path including a portion trained over said first engaging means, said first belt means mounting means including a first roller mounted in vertically spaced relation to said first engaging means, said first belt means trained over which said first belt means is trained, means ad- 25 jacent the leading end of the portion of said first belt means trained over said first engaging means and adjacent said first roller for engaging the plied combination after the same has been moved between said first engaging means and said first belt means portion and for 30 separating the copying material from the original, second engaging means for spacing the exposed copying material a predetermined distance from said developing means for development thereby, second belt means for receiving the exposed copying material and passing the 35 same into engagement with said second engaging means, means mounting said second belt means for movement in an endless path including a portion trained over said second engaging means, said second belt means mounting means including a second roller mounted in vertically 40 spaced relation to said second engaging means and adjacent said first roller over which said second belt means is trained, third belt means for receiving the separated exposed copying material from said separating means and moving the same over said first and second rollers and 45 thence between said second engaging means and the trailing end of the portion of said second belt means trained about said second engaging means, and means mounting said third belt means for movement in an endless path including a pair of vertically spaced rollers over which 50 said third belt means is trained, the portion of said third belt means extending between said pair of rollers engaging portions of said first and second belt means trained over 55 said first and second rollers.

2. Apparatus as defined in claim 1 wherein said first and second engaging means each comprises a drum mounted for rotation about its own axis at a peripheral speed substantially equal to the peripheral speed of the associated belt means.

3. Apparatus as defined in claim 1 wherein said development means consists solely of a source of heat.
